FOOT CUSHION

Garnett C. Skinner, Evanston, Ill.

Application March 23, 1948, Serial No. 16,607

5 Claims. (Cl. 36—71)

1

The invention relates to improvements in foot cushions.

An object of the invention is to provide a novel foot cushion construction in which the longitudinal, transverse, and metatarsal arches are flexibly supported.

Another object is to provide a construction for a foot cushion comprising a formed resilient shape-retaining frame member for yieldably supporting and cushioning the inner and outer longitudinal and transverse arches of a foot rested thereon.

Another object is to provide a foot cushion of such construction as to distribute body weight correctly.

Another object of the invention is to provide a foot cushion with means to grip the foot firmly to prevent transverse spreading of the foot and improper distribution of body weight.

Another object of the invention is to provide, in a foot cushion, a novel association of resilient arch-supporting means and cushions cooperating jointly to insure adequate support for all portions of the foot.

Other and further objects of the present invention will be apparent from the following description and claims, and are illustrated in the accompanying drawing which, by way of illustration, shows an exemplary embodiment and the principles thereof. Other embodiments of the invention embodying the same principle may be used, and structural changes may be made as desired by those skilled in the art, without departing from the present invention and the purview of the appended claims.

In the drawing:

Fig. 1 is a fragmentary side elevational view, partly in section, of a shoe, showing the improved foot cushion arranged therein.

Fig. 2 is a plan view of the foot cushion showing the top covering removed.

Fig. 3 is a perspective view of the arch-supporting frame.

Fig. 4 is a transverse sectional view, taken substantially on line 4—4 of Fig. 2.

Greater foot comfort may be obtained by the correct support of the foot so that body weight is absorbed and distributed by the longitudinal arches. Such distribution of the body weight is best obtained through the use of a foot cushion including a molded shape-retaining arch-supporting frame capable of limited adjustment through its inherent resiliency in response to applied body weight so as to snugly grip the foot and facilitate weight distribution to foot areas

2

intended to support such weight. Correct distribution of body weight allows the body to stand in a straighter and more upright position and allows for muscle relaxation at the posterior portion of the leg.

The bones and muscles of the feet, from heel to toe, lower when body weight is applied and rise to their original position when body weight is removed. Thus, it is apparent that foot health can be best maintained only when a foot support or cushion is capable of yielding under body weight. The foot cushion of the present invention yields in its entirety, providing a spring action for each arch and the heel bone thereof, thereby conforming to the natural functioning of foot movement. Accordingly, the foot cushion embodying the features of the present invention includes a formed resilient shape-retaining frame member to underly and support the longitudinal and transverse arches of the foot and resilient means such as pads to cushion the metatarsal arch and the heel bone.

Referring to the drawing in detail, the foot cushion illustrated is constructed as an insert for the shoe 10, although it will become apparent that it may be built directly into the shoe as a component part thereof. The shoe 10 includes the usual upper 11 and sole 12.

As best shown in Fig. 1, the improved foot cushion is in the form of an insert generally indicated at 13, which includes upper and lower covering layers of pliable material 14 and 15, such as soft leather, a resilient pad 16, preferably of suitable yieldable material such as foam rubber, a shape-retaining frame member 17, and a cushion 18. The pad 16, frame 17, and cushion 18 are held in proper relation between the upper and lower layers 14 and 15 by means of a row of stitches 19 which extend around the perimeter of the insert and firmly join the marginal edges of the upper and lower layers together. It should be quite evident, however, that the upper and lower layers may be suitably joined by means other than the stitches 19 and also that, in the event the foot cushion is incorporated into the shoe construction, the lower layer 15 may be entirely disposed of.

The frame member 17, which is best shown in Figs. 2 and 3, may be fabricated from any suitable shape-retaining material such as plasticized fabric, it being formed into substantially the shape best illustrated in Fig. 3 as by molding. As shown, the frame 17 includes a main body portion 21, which is suitably shaped transversely to conform substantially to the normal transverse

arch of a foot. Said body portion also is suitably curved and shaped longitudinally to provide a marginal area 22 which conforms substantially to the outer longitudinal arch of the foot and the opposite side thereof is suitably shaped, as at 23, to conform to the inner longitudinal foot arch. The posterior end of the frame 17 is formed with a deep end recess 24 defining spaced rearwardly extending arm portions 25 and 26. These arm portions constitute continuations of the shaped body portion and, when the frame is mounted in the assembly, the end portions of said arms are free for purposes to be described hereinafter.

The anterior end of the frame 17 also is provided with a relatively deep end recess 27 defined on one side by a forwardly extending arm 28 which, like the arm 25, constitutes a contour continuation of the inner arch curvature of the frame body. The free end portion of this arm also is substantially free. A forwardly extending portion 29 constituting the other side of the anterior recess 27 is substantially shorter than the related arm 28, this being effected by the sharp converging end or body edge 31.

The longitudinal edge of the frame 17 underlying the outer longitudinal arch of the foot is suitably provided with an integral upstanding flange 32 which is substantially coextensive with said body edge and the complementary edge of the posterior arm 26. Upon referring to Fig. 4, it will be noted that, when no pressure is applied to the frame 21 downwardly, the flange 32 lies in a plane angularly disposed outwardly of the vertical.

In assembly, the frame 17 is seated upon the pad 16. Upon reference to Fig. 2, it will be noted that the pad 16 has a contour outline corresponding substantially to the outline of the frame 17 in that it is provided with an anterior recess 33 in substantial alignment with the frame anterior recess 27. It should be observed, however, that there is no posterior recess in the pad 16; consequently, a substantial portion of said pad underlies the posterior recess 24 in the frame 17.

The pad and frame assembly is rested upon the bottom layer 15 of the foot cushion, which layer has a portion extending forwardly of the anterior end of said assembly. The cushion 18, previously referred to, and which is fabricated from suitable resilient material such as foam rubber or the like, is placed upon the forwardly extending portion of the lower layer 15, with its rearmost or small end portion located substantially within the registering anterior recesses 27 and 33. After these elements have been assembled in the relation discussed hereinabove, the top layer 14 of the foot cushion is positioned thereover and secured to the lower layer 15 in the manner hereinbefore described.

The foot cushion is positioned within the shoes, as shown in Fig. 1, with the posterior portion located at the heel thereof so as to locate the area of the pad 16 within the posterior recess 14 directly beneath the calcaneus indicated diagrammatically at 34. The body portion 21 of the frame underlies the longitudinal and transverse arches of the foot, thereby providing adequate support for the scaphoid 35 and internal cuneiform 36. The resilient cushion 18 underlies the phalanges, thereby affording a resilient supporting surface for maintaining and strengthening the metatarsal arch 37 of the foot. When pressure is applied downwardly on the body por-

tion, the free ends of the arms 25, 26 and 28 spread slightly.

The frame 17 serves not only to afford a firm but resilient support for the various foot arches, but it further provides means whereby the foot is firmly grasped when pressure is applied downwardly on the frame, as while walking. Upon reference to Fig. 4, it will be observed that the upstanding flange 32 swings inwardly into substantially the position illustrated in dotted lines at 38 when the body portion 21 of the frame is flexed in a downward direction. Such downward deflection of the body portion 21 also results in slight upward flexing of the inner longitudinal arch-supporting area 23. As a consequence, the foot is snugly embraced within the area defined by the inward flexing flange 32 and upwardly flexing portion 23. Such gripping of the foot prevents undue spreading thereof and, because the flesh is firmly held, the various muscles and bones of the foot structure are prevented from transverse displacement.

Although applicant has disclosed a specific structure and assembly of the improved foot cushion in the accompanying drawing and explained that structure in detail in the foregoing specification, it should be understood that details in the construction thereof may be varied without departing from the spirit of the invention or the scope of the appended claims.

I claim:

1. A foot cushion comprising upper and lower layers of pliable material, a molded longitudinal and transverse arch-supporting frame between said layers, said frame having cut-outs at its anterior and posterior portions and an upstanding flange on an edge of its longitudinal arch-supporting portion, a sheet of resilient material between the frame and the lower layer, said sheet conforming substantially to the outline of the frame and underlying the posterior cut-out, and a resilient phalanges-supporting cushion located in the anterior cut-out.

2. A cushion for underlying a foot and composed of upper and lower layers of pliable material, a resilient shape-retaining arch-supporting frame located beneath the upper layer, said frame being of sufficient size to underlie the longitudinal arches and extend rearwardly into the region of the heel of the foot, a resilient pad located between the supporting frame and the lower layer, the frame being cut out at its posterior end to expose the pad in the area beneath the heel bone, a cut-out at the anterior end of the frame, and a resilient cushion located in said cut-out between the upper and lower layers.

3. A foot cushion including a pad of resilient material, a frame member on said pad of resilient shape-retaining material arched so that its end portions constitute supports therefor and yieldably maintain its major portion elevated, the posterior end of the frame member including rearwardly extending arms defining therebetween a posterior recess exposing the underlying portion 65 of the pad, the extremities of said arms being free, the anterior end of the frame member including forwardly extending arms of different lengths defining an anterior recess corresponding substantially with an anterior recess in the pad, said arms being free, and a cushion disposed in the anterior recesses.

4. A foot cushion including a pad of resilient material, a frame member on said pad of resilient shape-retaining material arched so that its end 75 portions constitute supports therefor and yield-

ably maintain its major portion elevated, the posterior end of the frame member including rearwardly extending arms defining therebetween a posterior recess exposing the underlying portion of the pad, the extremities of said arms being free, the anterior end of the frame member including forwardly extending arms of different lengths defining an anterior recess corresponding substantially with an anterior recess in the pad, said arms being free, a cushion disposed in the anterior recess, and upper and lower covering members for the pad, cushion and frame member assembly.

5. A foot cushion comprising upper and lower layers of pliable material, a molded longitudinal and transverse arch-supporting frame between 15 said layers, said frame having cut-outs at its anterior and posterior portions and an upstanding flange on an edge of its longitudinal arch-supporting portion, a sheet of resilient material between the frame and the lower layer, said sheet 20 20 conforming substantially to the outline of the

frame and underlying the posterior cut-out, and a resilient phalanges-supporting cushion located in the anterior cut-out, the frame being yieldable upon applied pressure downwardly so as to draw the flange against the side of a foot when the latter is placed upon the foot cushion, said upstanding flange being substantially contiguous with one of the rearward projections.
